(57) **CLAIM**

The ornamental design for a sound generating device, as shown.

DESCRIPTION

FIG. 1 is a perspective front view of a sound-generating device showing my new design;

FIG. 2 is a perspective rear view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a top plan view thereof;

FIG. 8 is a bottom plan view thereof;

FIG. 9 is a top front perspective view of a sound generating device showing another embodiment of my new design;

FIG. 10 is a top rear perspective view thereof;

FIG. 11 is a front elevational view thereof;

FIG. 12 is a left side elevational view thereof;

FIG. 13 is a right side elevational view thereof;

FIG. 14 is a rear elevational view thereof;

FIG. 15 is a top plan view thereof; and,

FIG. 16 is a bottom plan view thereof.
